UNITED STATES PATENT OFFICE.

ROBERT T. WEBB, OF ST. LOUIS, MISSOURI, ASSIGNOR, BY DIRECT AND MESNE ASSIGNMENTS, OF ONE-FOURTH TO GEO. W. REED, JR., AND ONE-FOURTH TO LYNTON D. WYANT, OF TULSA, OKLAHOMA.

AUTOMATIC SAFETY CUT-OFF.

1,419,334.

Specification of Letters Patent. Patented June 13, 1922.

Application filed January 17, 1921. Serial No. 437,835.

To all whom it may concern:

Be it known that I, ROBERT T. WEBB, a citizen of the United States, residing at St. Louis, in the county of St. Louis City and 5 State of Missouri, have invented new and useful Improvements in Automatic Safety Cut-Offs, of which the following is a specification.

This invention relates to an automatic 10 safety cut off for automatically closing a pipe or passage carrying a fluid under pressure, when such pressure ceases or flows below a predetermined pressure degree.

One object of the invention is to provide 15 a simple, compact, satisfactory and safe means of automatically shutting off a gas or other fluid pressure supply when the pressure falls below any predetermined value or that required to give safe and satisfactory combustion, or when the supply fails 20 entirely.

A further object of the invention is to provide a valve device for the purpose described, combined with means for resetting 25 the same after closure for further operation and the resumption of the flow of gas or fluid.

The invention is particularly designed for 30 use in gas service systems, in which when the gas supply is temporarily cut off or obstructed to the extent that fires are extinguished, the outlets are left open and when the pressure again comes on the gas is free 35 to flow out. In the case of stoves and furnaces and some other appliances this is very inconvenient and dangerous. This invention provides a valve which is designed to automatically close the outlets under such 40 conditions and thus eliminate the inconveniences and danger such as now commonly exists.

The invention will be better understood by reference to the accompanying drawing, in which:—

45 Figure 1 is a vertical transverse section through one form of safety cut off embodying my invention.

Figure 2 is a section thereof taken in a 50 plane at right angles to that shown in Figure 1.

Figure 3 is a view in elevation of the cut off as applied in a gas service system.

Figure 4 is a sectional view of a modified 55 form of cut off.

Referring particularly to Figures 1, 2 and

3 of the drawing, 1 designates a valve shell or casing having an inlet 2 and an outlet 3 separated by a partition 4 formed with a port and valve seat 5. The said shell or casing is provided with an upstanding tubular portion 6, the lower part of which is suitably formed, as at 7, to form a guide for a vertically movable slideable valve 8, while the upper part thereof is internally threaded to receive a coupling member or plug 9. 60 The coupling member or plug 9 carries a frame portion 10 of a pressure chamber 11, the sides of which are formed by counterpart detachable cover plates 12. Arranged in proximity to the respective cover 65 plates are pressure diaphragms 13, limited in outward movement by said cover plates. These diaphragms may be of any suitable construction and marginally secured between the opposed surfaces of the frame 10 70 and cover plates 12.

The valve member 8 is suitably formed at its lower end to engage the valve seat and close the port 5, and is formed at its lower end with a passage 14 communicating with 80 a chamber or socket 15 formed in its upper portion. The said chamber 15 of the hollow valve thus constructed is in communication with a similar chamber 16 in the hollow plug 9, which is provided at its upper end 85 with a passage 17 connecting said chamber with the pressure chamber 11. A coiled spring 18 is arranged in the chambers 15 and 16 and exerts its expansive pressure to normally force the valve 8 downward to close 90 the port 5, said spring being compressed, however, when the pressure in the chamber 11 is above a predetermined point, to hold the valve elevated off the seat 5. When the valve is raised or unseated gas may flow 95 from a service pipe 19 through the inlet 2, port 5 and outlet 3 to a pipe or pipes 20 leading to the burner or burners 21 or other parts to be supplied with gas for service use. A portion of this gas also flows upward 100 through the passage 14, chambers 15 and 16 and passage 17 into the pressure chamber 11, thus forcing the diaphragms 13 outwardly or toward the walls or covers 12. Slidably and pivotally connected at their upper ends 105 to the respective diaphragms 13 are bell-crank levers 22 having at their lower ends short arms 23 which are suitably fulcrumed upon the frame 10, as indicated at 24. Links 25 (one for each lever) are pivotally coupled 110

at their upper ends to the lower ends of the respective levers 22, as indicated at 26, and at their lower ends to the valve 8, as indicated at 26', thus independently connecting each lever with the valve. When the diaphragms 13 are forced outward, the resulting movement of the levers 22 causes the pivot members 26 to be elevated, thus drawing on the links 25 and raising the valve 8 against the resistance of the spring 18, thus holding the valve open for service action and the spring under tension or compression. So long as this condition prevails, under a proper service pressure in the system, the valve will be maintained in open condition and gas may flow to the service fixtures for use in a manner previously explained. If, however, the pressure in the system should entirely cease or be reduced below a safe predetermined pressure, the valve will be moved to closed position by the expansion of the spring and the diaphragms will be moved inward in an obvious manner. The valve will thus totally cut off the flow connection between the burner or burners or other service fixtures and the service pipe 19, preventing the inconveniences and dangers arising upon a resumption of flow of gas in the system and requiring a manual resetting of the safety cut off and opening of the valve thereof before service conditions can be resumed.

In order to provide for a restoration of service conditions, after the valve 8 has been automatically closed, I provide the partition 4 with a by-pass port 27 connecting the inlet 2 and outlet 3, said port being controlled by a rotary plug valve 28 which is normally in closed condition. Said plug is provided with an external finger piece 29 and is normally held closed by a spring 30. By turning this valve 28 so that its passage registers with the port 27 gas will be allowed to flow between the inlet 2 and outlet 3 into the service system of the house or building in which the burners and automatic cut off are arranged, and a portion of this gas will flow upwardly into the pressure chamber 11. When the pressure in this chamber 11 reaches a predetermined degree the diaphragms 13 will again be forced outward to effect the opening of the valve 8, which will thereafter be held in such condition by the pressure of the gas, as long as such pressure is above the predetermined minimum limit, thus effecting a resumption of gas service to the burners or appliances to be supplied. When this is effected the valve 28 is released and the spring 30 automatically returns it to closed position and maintains it in such position until positively operated.

In Figure 3 I have shown the arrangement of the safety cut off in a service system as described, and in Figure 4 I have

shown a modified form of my invention which may be employed under some conditions. In this modified form of my invention I have disclosed a valve casing 1^a having an inlet 2^a, an outlet 3^a and a partition 4^a provided with a valve seat port and passage 5^a. At its top the valve casing has a tubular portion 6^a internally threaded to receive the externally threaded depending hollow stem 9^a of a casing 11^a closed at its top by a horizontal 70 detachable cover plate 12^a. The casing forms a pressure chamber 11^b and arranged therein is a suitable diaphragm 13^a marginally held between the opposed surfaces of the pressure chamber and the cover plate. Secured to the center of this diaphragm is a bracket 31 to which is pivoted the upper end of a link 32, said link being pivoted at its lower end to and within the tubular body portion of a hollow valve 8^a, said valve being suitably formed at its lower end for engagement with the seat of the port 5^a. Also connected with the bracket 31 is a stem 33 movable through an opening in a threaded plug 34 fitted in the cover plate 12^a and carrying at 80 its upper end a milled knob or finger piece 35. Encompassing the stem 33 between the central portion of the diaphragm and the lower end of the plug 34, and properly held and centered thereby, is a coiled spring 36, 90 which is adapted to be compressed on the upward movement of the diaphragm upon the adjustment of the valve 8^a to open position under service pressure, and which is adapted when the pressure ceases or flows below the safe minimum limit to expand and press the diaphragm and link downward and thus shift the valve 8^a to closed position. The operation of this device in maintaining the valve open and in automatically closing it to cut off connection between the service pipe and the burners or fixtures will be readily understood from the foregoing description. The device may be reset for use, after the valve has been closed, by the operator pulling upward through the knob or finger piece 35 on the stem 33, thereby raising the diaphragm and valve so that gas may flow into the pressure chamber until the desired pressure is reached to 105 maintain the diaphragm and valve in service position.

From the foregoing description, taken in connection with the drawing, the construction and mode of operation of my improved 110 automatic safety cut off will be readily understood, and it will be seen that the invention provides a simple, inexpensive, reliable and compact device of this character which may be readily installed in any gas 115 or other similar service system for the purpose of automatically cutting off communication between the fixtures to be supplied and the outside service pipe to prevent the inconveniences and dangers arising 120 130

from the inflow of gas, under ordinary conditions, when service flow in the outside system is again resumed. With my invention, as soon as the service pressure ceases 5 or flows below a safe limit, the supply of gas to the fixtures is automatically cut off and will be maintained in cut off condition until a person aware of the condition of affairs automatically resets the valve for a 10 resumption of gas flow.

Having thus fully described my invention, I claim:

1. The combination with a fluid pressure service system, of a casing having an inlet 15 and an outlet, a hollow valve for closing communication between said inlet and outlet, a fluid pressure chamber in communication with the inlet through the valve when the valve is opened and closed against 20 communication with the inlet when the valve is closed, a spring operating by expansion to close the valve, a pair of diaphragms in said pressure chamber, links connected to said valve and extending into said 25 pressure chamber, a pair of rock levers connected with said links, and the said rock

levers being connected with said diaphragms whereby movements of the latter will control the movement of the valve.

2. The combination with a fluid pressure 30 service system, of a casing having an inlet and an outlet, a hollow valve for closing communication between said inlet and outlet, a fluid pressure chamber in communication with the inlet through the valve 35 when said valve is opened and closed against communication with the inlet when the valve is closed, a spring tending normally to close said valve, a pair of oppositely disposed diaphragms in the pressure chamber, 40 links connected to said valve and extending into said pressure chamber, a pair of oppositely disposed bell crank levers in said casing, the ends of certain arms of said levers being secured to the casing and the ends of 45 the opposite arms of the levers being connected respectively to said diaphragms, and the intermediate portions of said levers being connected to said links.

In testimony whereof I affix my signature. 50

ROBERT T. WEBB.
